UNITED STATES PATENT OFFICE.

MERTON H. BLANK, OF INDIANAPOLIS, INDIANA.

INTERNAL-COMBUSTION ENGINE.

Original application filed March 19, 1921, Serial No. 453,545. Divided and this application filed January 9, 1922. Serial No. 528,104.

This invention relates to internal combustion engines and is especially concerned with engines of the closed V type as disclosed in my copending application Serial No. 453,545 filed March 19, 1921, of which this application is a division.

One object of the invention is to provide a head for an internal combustion engine in which the heat absorbing, conducting and transmitting properties of the metal composing the head are utilized to an increased extent, especially in connection with the preheating of the explosive gas mixtures.

Another object is to provide an intake manifold for an internal combustion engine which is contained within the engine and the walls of which are protected from direct contact with the outside air from their junction with the carburetor to the combustion chamber and are surrounded by heated fluids.

Another object is to construct an improved head for an internal combustion engine in which intake and exhaust manifolds are incorporated and so arranged relative to each other that the intake manifold is jacketed in part by the exhaust manifold and in part by the cooling water chamber.

Another object is to provide a new and improved construction, location and arrangement of intake and exhaust manifolds whereby gases may be conducted from a carburetor to the combustion chambers and thence to an exhaust tube or muffler with the use of a minimum number of separate parts.

Other objects will be pointed out herein-after.

In general my invention contemplates a new and improved construction and arrangement of tubes, conduits or manifold parts for an internal combustion engine resulting in a new method of conducting fuel gases to the cylinders and novel means of suitably regulating the temperature of such gases, as well as a simplified structure requiring a minimum number of separate parts.

One form of engine construction embodying my invention is disclosed in the drawing accompanying and forming a part of this specification in which;

Fig. 1, is a fragmentary, transverse sectional view of an engine constructed in accordance with my invention.

Fig. 2 is a fragmentary, longitudinal section, as taken on lines 2-2 of Fig. 1.

Figs. 3 and 4 are respectively plan sections of the head unit taken on lines 3-3 and 4-4 of Fig. 5.

Fig. 5 is a central, vertical, transverse section showing assembled cylinder block and head units, as taken on lines 5-5 of Figs. 3 and 4.

Figs. 6 and 7 are fragmentary views of the head unit taken on lines 6-6 and 7-7 of Fig. 3.

The engine illustrated in the drawings consists in part of crank case unit 2, cylinder block unit 3 and head unit 4. A suitable crank shaft (not shown) is mounted in bosses 70 carried by unit 2 and has connecting rods 5 and pistons 6 connected therewith in the customary manner. 7 indicates a cam shaft carried by unit 2 in a position to actuate valve operating mechanism designated generally by 8.

Cylinder block unit 3 consists of a hollow shell with a plurality of cylinders 9 extending therethrough and surrounded for part of their length by a cooling fluid chamber 80 10. At 11 is indicated a transverse wall within the interior of unit 3 and between cylinders 9. This wall which has a cored passage 12 extending lengthwise thereof joins the side wall 13 and top wall 14 of unit 85 3, the passage 12 thus leading through the unit from an opening 13a in the outer side wall 13 to opening 15 in the top wall 14. Preferably, in the engine shown, wall 11 and its passage 12 are located intermediate the 90 ends of the unit, opening 15 being approximately in the middle of top wall 14. Cover plate 16 fitted to the side of unit 3 has an opening 17 coinciding with opening 13a and a second opening 18 which similarly communicates with a short passage 19 leading from side wall 13 to top wall 14 of the unit. To the outside face of cover plate 16 is attached a jacketed tube or elbow 20, the passage 21 therethru forming a continuation of 100 passage 12 while the jacket chamber 22 communicates with passage 19. 23 which indicates an outlet tube from jacket chamber 22 may, if desired, be equipped with a stop cock (not shown). A carburetor (not 105 shown) may be attached to elbow 20.

Head unit 4 is a hollow shell provided with intake and exhaust manifolds in the

interior thereof, the space 25 between the manifolds and walls of the unit being provided for the circulation of cooling fluids. Intake manifold 26 consists of a short vertical passage 27 arranged to register with opening 15 of passage 12 to form a continuation of that passage. From the top end of passage 27, passages 28 extend for a short distance substantially parallel to each other and longitudinally of the unit, the top wall 29 of the unit comprising one wall of the passages. From each of these passages 28, branch passages 30 lead downwardly and open into cylinders 9 through openings 31 closed by valves 32.

The exhaust manifold is composed of parallel longitudinally extending passages 33 each of which communicates with certain cylinders 9 through branches 34 and outlet openings 35 controlled by valves 36. Adjacent the rear end wall 37 of unit 4 passages 33 unite and have a common outlet opening 38 through the wall. An exhaust tube 39 and muffler (not shown) may be attached to wall 37 indicated in Fig. 2.

Exhaust manifold 33 lies in a horizontal plane just below that of intake manifold 26 the two being adjacent, and preferably having a common dividing wall throughout substantially the entire length of the latter.

From one exhaust passage 34 a^a an auxiliary passage 40 leads to bottom wall 41 of unit 4 to connect with passage 19 and form a path for leading exhaust gases to jacket chamber 22 of elbow 20.

It will be observed that my improved arrangement of passages for both intake and exhaust gases are adapted to utilize the heat conducting properties of the metals composing the units in insuring economical fuel consumption. Provision is made for heating the incoming fuel from the time it leaves the carburetor until it enters the combustion chambers of the cylinders but undue heating is prevented so that the volumetric efficiency of the gases which enter the combustion chamber is not materially diminished. Jacketed elbow 20 serves to heat the fuel coming from the carburetor but passage 12 which is surrounded by cooling fluid maintains the gas at a moderate temperature due to the fact that the surrounding cooling fluid has just returned from the radiator and has not become highly heated. In head unit 4 the intake manifold 26 and its branches have their bottom walls in contact with the exhaust gases while their sides and top are being cooled by fluids such as air and water, the result of this structure being that any particles of unvaporized fuel which collect on the bottom of the passages will be vaporized at once but the gases will not become overheated due to contact with the other walls which are somewhat cooler because of the circulation of cooling fluids therewith.

Preferably head unit 4 and if possible block unit 3 are composed of aluminum alloys or other good heat conducting metal to ensure uniform distribution and rapid cooling of the exhaust gases and to prevent unequal heating of the fuel. 70

By my improved arrangement and location of manifolds and passages a carburetor may be connected to a multiple cylinder engine with at most a single intermediate 75 member, thus eliminating many extra parts now in common use.

Although I have shown and described in detail a specific form of V type engine in which my invention is embodied I do not 80 wish to be understood as limiting my invention thereto. The scope of my invention is defined in what is claimed.

What I claim is:

1. In an internal combustion engine in combination, a cylinder block unit comprising a plurality of cylinders, a plurality of conduits extending through the said unit, a hollow head unit for the said block unit, intake manifolds within the said head unit and communicating with one of the said conduits in the block unit, and exhaust manifolds within the head unit having an outlet opening through an end wall thereof, and an auxiliary outlet opening communicating 95 with another of the said conduits.

2. In an internal combustion engine in combination, a cylinder block unit, two conduits extending through the said unit, a hollow head unit, intake and exhaust manifolds within the head unit and communicating one with one of the said conduits and the other with the other of said conduits, and a jacketed tube attached to the said block and in communication with each of 105 the said conduits.

3. In an internal combustion engine in combination, a cylinder block unit comprising a plurality of cylinders, two conduits extending through the said unit, a hollow head unit for the said block unit comprising interiorly arranged intake and exhaust manifolds, the intake manifold communicating with one of the said conduits and the exhaust manifold communicating with 115 the other conduit, and a jacketed tube secured to the block unit and communicating with one of the said conduits.

4. In a multiple cylinder internal combustion engine in combination, a cylinder block unit, an intake and an exhaust conduit extending therethrough, a hollow head unit, and intake and exhaust conduits in said head communicating with the respective conduits in the block, said intake conduit in said head being arranged above said exhaust conduit, a portion of the walls of each of said conduits being common. 120

5. In a multiple cylinder internal combustion engine in combination, a cylinder 130

block unit, an intake and an exhaust conduit extending therethrough, a hollow head unit, and intake and exhaust conduits in said head communicating with the respective conduits in the block, said intake conduit in said head being arranged above said exhaust conduit, a portion of the walls of each

of said conduits being common, said intake and exhaust conduits being in a substantially horizontal plane. 10

In testimony whereof I hereunto affix my signature.

MERTON H. BLANK.
